UNITED STATES PATENT OFFICE.

DONALD S. BARROWS, OF ROCHESTER, NEW YORK, ASSIGNOR, BY MESNE ASSIGNMENTS, TO THE SYMINGTON COMPANY, A CORPORATION OF MARYLAND.

CARRY IRON.

Application filed August 7, 1924. Serial No. 730,689.

The invention relates to draft rigging for railway cars and more particularly to means for supporting the coupler at points adjacent the coupler head, said means being 5 adapted to cooperate with flanges formed on the center sills, said flanges furnishing the support for said means.

The principle object of the invention, generally considered, consists in combining 10 with center sills of a railway car having oppositely directed flanges at their lower ends, a carry iron adapted to bridge the space between the sills, said carry iron having portions cooperating with the flanges of 15 each center sill and additional portions cooperating with the sill web.

Another object of the invention is to provide a carry iron having adjacent its ends recessed portions adapted to receive the adjacent sills together with means for connecting said carry iron to said sills.

A still further object of the invention is to provide a carry iron adapted to cooperate with the coped inner flanges of the center 25 sills of the A. R. A. standard car, said carry iron having portions extending longitudinally thereof, said extending portions being adapted to cooperate with the outwardly directed flanges of said car sills, and means 30 for connecting the carry iron to said sills.

In the drawings wherein I have illustrated a preferred embodiment of the invention:

Figure 1 is an end elevational view showing the center portion of the car and showing the carry iron in position and the coupler in cross section;

Figure 2 is a cross sectional view of Figure 1 taken on the line 2—2 of Figure 1, 40 the direction of view being indicated by the arrows adjacent the ends of said section line;

Figure 3 is a side elevational view; and

Figure 4 is a cross section on the line 4—4 45 of Figure 2.

Throughout the several views like parts are designated by like reference characters.

In the drawings the numeral 1 designates a portion of a car end framing and 2 an angle bar connected to the end framing by the rivets 3, said angle bar bridging the space between the center sills 4 and being connected to the upper out-turned flanges 5 thereof by the rivets 6. Extending transversely of the sills 4 and connected thereto,

preferably by means of rivets 7, is a striking casting 8 which may be of any desired form and which in fact forms no part of the invention.

At their lower ends, the sills 4 are provided with out-turned flanges 9 and with inturned coped flanges 10. It might be noted that the sills 4 are of the so-called special I-beam type and the inturned flanges 10 thereof are coped or cut away, as in the standard A. R. A. car, from the end of the sills to a point adjacent the rear end of the cushioning mechanism so as to permit insertion and withdrawal of the cushioning mechanism from between the sills upon the detachment of the cushioning mechanism supports.

The sills 4 preferably extend to a point flush with the forward flange of the angle bar 2 although it will of course be understood that by center sills as used throughout the specification and claims, I do not limit the invention to cars in which continuous center sills extending from car end to car end are employed and that by the term center sills I intend to include also such construction where the center sills terminate at points intermediate the car ends and short stub sills or draft sills are employed.

The carry iron is generally designated by 85 the reference numeral 11 and comprises a trussed or flanged bar 12 having depending therefrom and preferably adjacent the side edges thereof, the trusses or flanges 13 and 14. The bar 12 is provided at points adjacent the inner faces of the sills 4 with upturned flanges 15 and may, if desired, be provided adjacent the lower ends of the said flanges with thickened portions 16 which are adapted to conform to and overlie the adjacent portions of the flanges 10. The flange 13 extends upwardly and is integrally connected to the forward edge of the flanges 15 and extends longitudinally of the carry iron a distance substantially equal 90 to the extent of the flanges 9 of the sills 4. Integrally connected with the extending portions of the flange 13 I provide the carry iron with angle flanges 17 and 18 which 95 extend rearwardly from the flange 13, the flanges 17 being upright and being adapted to engage the outer faces of the webs of the sills 4 while each flange 18 is adapted to overlie and conform to the adjacent face of the out-turned flanges 9 of the said sills.

100
105
110

The flanges 18 are provided with apertures 19 through which and through corresponding openings 20 in the flanges 9 are received the securing bolts 21 by means of which the 5 carry iron is maintained in position against outward movement. The bolts 21 may be provided with nuts 22 and to prevent the accidental misplacement of the nuts locking devices 23 consisting of Z-bars may be employed.

To obviate wear from the coupler 26 on the bar 12 of the carry iron, I provide a wearing shoe 24 which may be of channel-shape so as to overlie the bar 12 and to be 15 maintained in position by the depending flanges 25 of the said shoe.

From the foregoing description taken in connection with the drawing, it will be observed that there is provided at each end 20 of the carry iron supports 16 and 18 which are adapted to overlie and seat respectively upon the flanges 10 and 9 of the draft or center sills. It will also be observed that the carry iron is maintained against inward movement by the engagement of the flange or truss member 13 with the end faces of 25 the sills and that it is maintained against outward movement by means of the bolts 21. The construction is exceedingly simple and by providing, as noted, a plurality of 30 bearings engaging the sill flanges, the weight of the coupler and the pressure from the coupler due to angling movements, are adequately supported and at the same time 35 the carry iron is simply and easily detached from the car by the removal of the bolts 21. It might be observed that the wearing shoe 24 prevents all wear upon the material of 40 the carry iron and that additional wearing shoes may be easily applied as desired. It is also to be noted that if desired, shims may be inserted between the carry iron and the wearing shoe so that the height of the

coupler may be adjusted to compensate for the set of the truck springs. 45

Having now described my invention, I claim:

1. In a draft rigging, the combination with center sills having oppositely directed lower flanges, of a coupler, and a carry iron 50 therefor, the end portions of said carry iron being adapted to embrace the adjacent portions of said sills and overlie the said flanges.

2. In a draft rigging, the combination 55 with center sills having oppositely directed lower flanges, of a coupler, and means for supporting the same, said means including a member bridging the said sills and supported by the inner flanges thereof, said member being in abutting engagement with the forward faces of said sills.

3. In a draft rigging, the combination with center sills having oppositely directed lower flanges, of a coupler, a carry iron 65 therefor, said carry iron having, adjacent its ends, portions adapted to overlie the said sill flanges without intersecting the webs thereof, and means for removably connecting the said carry iron to some of said 70 flanges.

4. The combination with center sills having inwardly directed lower flanges, of a coupler, and a carry iron for supporting the same, said carry iron comprising a substantially U-section member, the web of said member being adapted to overlie the said 75 sill flanges.

5. A coupler carry iron comprising a trussed beam having upright sill engaging 80 flanges, and a plurality of substantially horizontally extending flanges, said last named flanges being adapted to support said carry iron in position.

In testimony whereof I affix my signature.

DONALD S. BARROWS.
